POSTER DISPLAY MEANS

Filed April 20, 1928

UNITED STATES PATENT OFFICE

CASTRO M. DABROHUA, OF CHICAGO, ILLINOIS

POSTER DISPLAY MEANS

Application filed April 20, 1928. Serial No. 271,483.

My invention relates to improvements in supporting means for posters.

The object of my invention is to provide a simple collapsible easel support for a poster and improved means for readily mounting a poster on the support for displaying the poster.

A particular feature of my improvement resides in a simplification of construction and reduction of parts over the form disclosed in the co-pending application filed jointly by myself and William E. Roberts on April 7, 1927, Serial Number 181,822.

In my present invention, I make use of the metal strips commonly used at the ends of posters providing openings for receiving the ends of the support parts.

One feature of importance consists in the formation of the strips on the ends of the posters adjacent to the openings in such a manner that the ends of the support can be easily entered through the openings beneath one wall of the strips.

Another idea involved is that of hooking the support to the poster at least at one end for the purpose of assisting in mounting the poster on the support.

Other novel features will be made clear by the following description taken in conjunction with the accompanying drawings forming part of this specification and in which—

Fig. 1 is a perspective view illustrating my improved poster display means;

Fig. 2 is a plan view of the supporting device shown in collapsed condition;

Fig. 3 is an enlarged fragmentary view showing the means connecting the parts of the supporting device;

Fig. 4 is a transverse section on the line 4—4 of Fig. 3;

Fig. 5 is a longitudinal section on the line 5—5 of Fig. 3;

Fig. 6 is a view similar to Fig. 5 but showing the parts before the device is fully extended;

Fig. 7 is a fragmentary section on the line 7—7 of Fig. 1;

Fig. 8 is a fragmentary elevation show-

ing the upper end of one of the support members in engagement with the poster;

Fig. 9 is a fragmentary longitudinal section on the line 9—9 of Fig. 8; and

Fig. 10 is a view similar to Fig. 8 but showing the engagement of one of the lower ends of the support with the poster.

In said drawings 1 illustrates a poster, usually consisting of a sheet of paper and having a reinforced upper end 2 and a similarly reinforced lower end 3, supported in display position by a supporting device 4 embodying my invention in one form.

As best shown in Fig. 6, the reinforcing at the ends of the poster consists of thin metal strips 5 folded over upon themselves and upon the ends of the poster to provide three layers 6, 7 and 8 of the sheet metal.

The layer 6 overlies the rear of the poster 1 and the layer 7 lies between the other two layers. The fold 9 between the two layers 7 and 8 provides a smooth finish to the strip at the face of the poster and the fold 10 between the layer 8 and the rear layer 6 provides a smooth end for the completed poster. The layer 7 lies beneath or inside of the rear layer 6 and provides a wall to limit the insertion of the ends of the device 4 as hereinafter more fully explained.

The supporting device 4 consists of two main members 11 and 12 made of wire. These members 11 and 12 are each U-shaped in form and provide free ends adapted to engage the poster when the device is arranged to support it. The member 11 is bent at its middle portion to form it into U-shape having a cross bar 13 and two legs 14. There is a sheet metal connection plate 15 which has its edge portions 16 formed around the legs 14 and which provides a guide for the member 11 so that it can be slid longitudinally relatively to the member 12 from a collapsed relation, as shown in Fig. 2, to an extended poster supporting relation shown in Fig. 1.

The member 12, which forms the lower portion of the device, is bent between its ends at 22 to form two legs 17 having free ends 17' for engagement with the lower reinforcement or binding strip 3, and a middle

brace part 18 which is U-shaped having a lower cross bar 19, forming a foot part and upwardly extending side parts or legs 19'. These two members 17 and 18 are joined at their upper ends at 22. The upper end portions 20 of the legs 17 are enclosed with the adjacent parts of the upper part 11 by the formed over edges 16 of the connecting plate 15 but unlike the upper member 11 which is slidable in relation to the plate 15, the lower member is fixed against movement. This is accomplished by bending the legs 17 to form shoulders 21 at the lower end of the connecting plate 15 and by the bends 22 at the upper end of the plate 15.

The free ends 23 of the legs 14 of the upper member 11 are bent toward each other in the plane of the device and flattened out as shown to form thin hooked ends, and the free ends 17 of the lower member are flattened out but not formed into hooks. The flattening of these ends is for the purpose of facilitating their engagement with the reinforcing strips at the ends of the poster.

The rear wall or layer of the end strips is provided with holes or openings 24 in the upper strip and openings 25 in the lower strip for permitting the engagement of the strips by the ends of the supporting device, and although with the ends flattened out, as described, they might be forced under the rear walls of the strips, I prefer to form these rear walls outwardly as shown at Figs. 8 and 9, and at 27 Fig. 10.

It will be noted that the raised parts 26 on the upper strip are on the adjacent sides of the two openings 24 in position to receive the hooked ends 23 of the upper member. The raised parts 27 on the lower strip 3 are at the lower sides of the openings 25.

While the cross bar 19 of the lower member might be made straight, I prefer to curve it up between its ends, so that the ends 28 only will rest upon the supporting floor, thus making the device more rigid when set up.

The upper or inner end of the brace member 18 is formed so that the upper end portions 30 of the sides 19' of the brace member naturally lie in a position separated from the front side of the connection plate 15 and just below the lower end of this plate these parts are bent rearwardly as shown at 31, Fig. 6.

As the upper member 11 is drawn upwardly its cross bar 13 at its lower end contacts with these formed out parts of the member 18 and forcibly pushes or cams the brace 18 rearwardly against the resiliency of the said member. This contact produces sufficient friction between the parts to prevent the collapse of the device when installed on a poster.

In applying the support to a poster, the upper member 11 is first pulled out to its

limit and the bent prongs or ends 23 are entered into the openings 24 in the upper bending strip. The legs 14 of the upper member 11 have to be sprung apart to enter the prongs 23 and the resiliency of the member holds the legs in engagement with the strip. Preferably the poster is laid flat down on a table on its face when applying the support to its back. After the bent ends of the member 11 have been engaged with the upper strip, the device being fully extended is bowed up to shorten it enough to permit the free ends 18 of the lower member 12 to be entered into the openings 25 in the lower strip.

The device as a whole when extended is enough longer than the poster so that it is retained in a bowed-up condition as shown in Fig. 1, exerting a pull on the poster which keeps it flat.

As many modifications of my invention will readily suggest themselves to one skilled in the art I do not limit or confine my invention to the specific details of construction and operation herein shown and described except within the scope of the appended claims.

I claim:

1. In a poster support of the kind described, two longitudinally relatively movable resilient members, each having two laterally spaced ends for engagement with a poster, one of said members being formed back upon itself to provide a brace, the brace normally lying substantially in the plane of the member and provided with formed up cam portions adapted to be engaged by the other relatively movable member as it approaches its extended position and whereby the brace member is forced out of the plane of the device to serve as an inclined brace to support the device and an attached poster in substantially vertical position.

2. In a poster support of the kind described, two U-shaped members made of wire, one of said members comprising a pair of substantially parallel legs and an intermediate U-shaped brace part, a connecting plate fixed on this member at the junction of the legs and brace part, the second U-shaped member comprising a pair of legs connected by a cross bar, the side edges of the connecting plate formed to provide guides for the legs of said second member, the brace member formed to provide cam projections for engagement by said cross bar as the second member is extended and whereby the brace member is forcibly swung to bracing position and friction is provided for retaining the device extended.

3. A poster having folded sheet metal binding strips at opposite ends, in combination with a tensioning device for the poster, the rear walls of the strips provided with perforations, the walls of the strips adja-

cent to the openings being formed slightly outwardly, the tensioning device having relatively thin ends adapted to be entered through said perforations and beneath the formed-out walls of the strips, the tensioning device adapted and arranged to be placed under compression to be engaged with the poster.

4. A poster having folded metal binding strips at opposite ends, in combination with a tensioning device for the poster, the rear walls of the strips provided with perforations, the walls of the strips adjacent to the openings being formed slightly outwardly, the tensioning device having legs which are bent at their ends to form opposed hooks at one end of same, the hooks having relatively thin ends adapted to be entered through said perforations and beneath the formed-out wall of the strip, and the device having legs with flattened ends at the opposite end of same adapted to be entered through said perforations and beneath the formed-out wall at the opposite end of the poster, the device arranged and adapted to be placed under compression to be engaged with the poster.

5. A poster having folded metal binding strips at opposite ends, in combination with a tensioning device for the poster, the rear walls of the strips provided with perforations, the walls of the strips adjacent to the openings being formed slightly outwardly, the device—at at least one end—having ends which are formed into relatively thin opposed hooks extending in the plane of the device and adapted to be entered through the perforations in the upper strip and beneath the formed-out wall of the strip, and at the other end of the device, ends adapted to be entered beneath the formed-out wall of the lower strip, the device being longer than the poster and necessitating the bowing of the device to place it in poster engaging position and whereby the poster is tensioned.

In witness that I claim the foregoing as my invention, I affix my signature this 2nd day of April, 1928.

CASTRO M. DABROHUA.
